United States Patent Office.

FRANZ RUDOLPH WEGMAN, OF SAXONY, ASSIGNOR TO HIMSELF AND
TOBIAS KOHN, OF HARTFORD, CONNECTICUT.

Letters Patent No. 79,040, dated June 16, 1868; patented in Saxony, March 6, 1865.

IMPROVED WIRE-SPRING MATTRESS.

The Schedule referred to in these Letters Patent and making part of the same.

TO ALL WHOM IT MAY CONCERN:

Be it known that I, FRANZ RUDOLPH WEGMAN, of the Kingdom of Saxony, have invented a new and useful Wire-Spring-Mattress; and I do hereby declare that the following is a full, clear, and exact description of the same, reference being had to the accompanying drawings, and to the letters of reference marked theron.

Figure 1 shows a side view of the wire-spring mattress stretched upon its frame.

Figure 2 shows a section across the mattress and frame, from side to side.

Figure 3 shows an enlarged view of the wire braiding of which the mattress is formed.

My invention consists in constructing a mattress of spiral wire springs, linked or braided together, and stretched upon a frame, so as to form a spring-bed.

The springs are made of steel or other wire, wound into a spiral form by proper machinery, and linked together, so that each convolution of the spring passes through two or more of the adjoining springs, as shown at B in fig. 3.

The spiral wire springs will ordinarily be arranged double, as shown at B in fig. 3, that is, consisting of two series of springs interwoven together, so as to form one web of woven wire. This can extend over the whole mattress, or only across the top, where the principal strain comes, the sides being made in some other way, if desired, as shown at A, fig. 3. A greater number of spirals can be linked together, if desired, to give a greater strength and stiffness to the web of braided wire.

The iron frame upon which the springs are stretched consists of two parallel angle-irons C C, connected by four round bars D E F G. At the head and foot are vertical frames, to which the ends of the spirals are firmly attached.

The side spirals are attached to the bars C C by a rod run through the outside spiral, and secured by staples, or otherwise, to the angle-irons C C.

The wire mattress is made several inches shorter than the frame, so that it can be stretched over it. After the ends of the coils are firmly secured to the head and foot of the frame, the mattress is stretched, by inserting the struts H H, which rest against the top corners of the frame, and against the round bars E and F.

My invention can also be used for cushions to sofas, lounges, chairs, or any other articles of furniture to which spring-cushions are applicable.

Claims.

What I claim as my invention, and desire to secure by Letters Patent, is—

1. A mattress or cushion, composed of spiral wire springs, braided or linked together in two or more series, so as to form one connected web of woven wire, substantially as herein described.

2. The combination of the struts H H with a mattress of wire springs, substantially as described, for the purpose of stretching it and rendering it more elastic.

FRANZ RUDOLPH WEGMAN.

Witnesses:
